UNITED STATES PATENT OFFICE.

EDWARD M. BUTLER, OF CROTON FALLS, NEW YORK, ASSIGNOR TO STEWART B. BUTLER, OF CROTON FALLS, NEW YORK.

CUFF LINK.

Application filed October 25, 1919. Serial No. 333,198.

To all whom it may concern:

Be it known that I, EDWARD M. BUTLER, a citizen of the United States, residing at Croton Falls, in the county of Westchester 5 and State of New York, have invented a new and useful Cuff Link, of which the following is a specification.

The object of my invention is to provide a novel, conveniently adjusted resilient cuff 10 link adapted to permit of pulling up the shirt sleeves without unfastening the cuff button, and to hold the sleeve above the elbow without the use of an arm elastic.

In the accompanying drawings illustrating my invention—

Figure 1 is a perspective view of the invention applied to a cuff;

Fig. 2 is a side elevation of same;

Fig. 3 is a section on line 3—3 of Fig. 2; 20 Fig. 4 is a side elevation of a modified form of the invention;

Fig. 5 is a view partly in elevation and partly in section of the form shown in Fig. 4, and

Fig. 6 is an enlarged detail view of the hook on the end of the coiled spring.

Like numerals designate like parts in each of the views.

Referring to the accompanying drawings, 30 I provide suitable buttons 1 and 2 having like eyes 3, engaged by the hooked ends 5 of a suitable coil spring 4, or equivalent resilient member. Hooks 5 are bent as shown in Fig. 6, with the ends close to the 35 buttons to prevent their becoming accidentally detached. The hooks 5 are close to the coil spring 4 and only long enough to engage the eyes 3 of the buttons.

Referring to Figs. 4 and 5, I provide a tube 9, attached by a hook 5 to the eye 3 of one of the cuff buttons 2, while to the eye 3 of the other cuff button is detachably engaged hook 5 of rod 6, which carries an end washer 7 that engages the end of a suitable coil spring 8, the other end of 45 spring 8 being engaged by the opposite end 10 of metal tube 9.

What I claim is:

1. In a cuff link, the combination of cuff buttons having eyes mounted thereon, a metal tube having a hook attached to one end and adapted to detachably engage the eye of one of the cuff buttons, a rod having a washer fixed to one end and having a hook at the other end, adapted to detachably engage the eye of the other cuff button, the aforesaid washer being slidably mounted within the metal tube, and a spring resiliently bearing against the washer and against the other end of the tube, whereby to provide a resilient cuff link of attractive appearance in which the spring is concealed and protected by a metal tube, substantially as set forth.

2. In a cuff link, the combination of cuff buttons having corresponding eyes, hooks detachably connected to the respective eyes resilient means associated with one of the aforesaid hooks connected with the eyes for permitting of a resilient movement of one button apart from the other, and metal tubular means completely enclosing the resilient means, substantially as and for the purposes hereinbefore described.

EDWARD M. BUTLER.
